UNITED STATES PATENT OFFICE.

FRED J. MILLER, OF SUSIE, WYOMING, ASSIGNOR OF ONE-HALF TO CHARLES C. LEHMER, OF MARBLETON, WYOMING.

AUTOMATIC CAR STOP OR BRAKE.

1,201,849.

Specification of Letters Patent.

Patented Oct. 17, 1916.

Application filed November 18, 1913, Serial No. 801,718. Renewed March 31, 1916. Serial No. 88,172.

To all whom it may concern:

Be it known that I, FRED J. MILLER, a citizen of the United States, residing at Susie, in the county of Lincoln and State of Wyoming, have invented new and useful Improvements in Automatic Car Stops or Brakes, of which the following is a specification.

This invention relates to an automatic car stop or brake, designed particularly for use in connection with mining or other cars traveling on tracks extending along slopes or inclined planes, the object of the invention being to provide means whereby when a train breaks apart and one or more cars begin to run away down the slope, automatic means will be thrown into action to stop the same.

A further object of the invention is to provide novel brake or stop mechanism on each car, including a brake device to engage coöperating brake devices in the track, together with a latch for holding the brake device on the car normally elevated and inactive, and means coacting with the latch whereby in the event of the separation of cars the latch upon the car which has broken away will be retracted to free the brake device thereof for action, while the brake mechanism on the car in advance thereof will remain inactive in order to prevent damage or derailment of the car or cars still remaining coupled to each other and to the draft cable.

The invention consists of the features of construction, combination and arrangement of parts herein fully described and claimed, reference being had to the accompanying drawings in which:

Figure 1 is a side elevation of adjoining cars showing the application of the invention; Fig. 2 is a bottom plan view of one of the cars showing the parts in normal position. Fig. 3 is a vertical longitudinal section on the line 3—3 of Fig. 2. Fig. 4 is a view similar to Fig. 3 showing the brake device on the car released for action and the parts of the friction coupler disconnected. Figs. 5 and 6 are views of the parts of the friction coupler on an enlarged scale.

Referring to the drawings, 1 designates a mining or other similar car, provided as usual with the draw bar 2, adapted to be connected by link-and-pin or other desired

coupling devices 3 to other similar cars, as in the connection of a number of cars together to form a train. Arranged at suitable intervals between the rails 4 of the track, at points where rails extend along a slope or inclined plane, are relatively stationary brake members 5, which are secured to the ties 6, and each of which is provided with an inclined upstanding projection 7.

Each car equipped with the invention is provided with a bail-shaped grapple or brake member 8 for engagement with the projections 7 of the stationary brake members 5, the free ends of the arms of said brake member being pivotally mounted upon some suitable portion of the car, as upon an axle 9. The member 8 normally lies against and in parallel relation to the bottom of the car and is adapted to be released and to drop by gravity so as to engage one of the brake members 5 to prevent the car, in the event of its separation from the train or another car, from descending the slope.

The braking member 8 is adapted to be held elevated or in retracted position by a hook shaped dog or latch 10, which engages the cross bar 11 thereof. This dog or latch member is connected with a longitudinally extending controlling rod 12. The rod 12 extends through a guide tube 13, suitably secured to the under side of the car body or to the draw bar 2, and projects at its opposite ends beyond said tube. The spring 14 is inclosed within the tube and terminally engages suitable abutments 15 and 16 on the tube and rod to slide the rod in rearward direction and maintain it in normal position with the dog or latch 10 in engagement with the cross bar 11 of the brake device 8.

The ends of the rod terminate in flattened reduced portions 17, each having a transverse perforation 18. To the rear end of the rod is attached one member 19 of a friction coupling device, adapted for co-operation with a companion coupling member 20, the forward end of the rod of each car being provided with such a coupling member 20, which is provided with a pivoted bail or link 21 detachably engaged by a snap hook 22 on a chain or other flexible connection 23 having a ring 24 or the like engaging the perforation 18 in the end of the rod, it being understood that the cou-

pling member 20 upon the front end of a car is adapted for engagement with a coupling member 19 on a preceding car. The snap hook or equivalent connection 22 between the coupling chain 23 and coupling member 20 permits of the coupling member being conveniently removed when occasion requires so that a worn or damaged coupling member may be easily repaired and re-applied or a new one substituted in its place. Each coupling member 19 has a bifurcated rear portion 25 which receives and embraces the reduced end of the rod 12 and pivotally connected therewith by a bolt 26, which passes through the opening 18 in the said end of the rod and through registering openings in the arms of the bifurcation and has its forward portion formed to provide a longitudinally tapered tongue 27 which is adapted to fit within a slot 28 in the coating coupling member 20. The slot 28 in the member 20 is correspondingly and reversely tapered to the taper of the member 19, whereby a frictional binding action between the sides, tongue and walls of the slot is instituted to normally hold said coupling members connected against longitudinal separation. The member 20 is adapted to be placed with its slot in alignment with the upper surface of the tongue and to be slipped downwardly into engagement therewith, thus effecting a coupling connection. Preferably the member 19 is provided with a stop 29 to hold the member 20 from undue downward movement.

In practice, when two or more cars are coupled together to form a train, the forward end of the controlling rod 12 of each rear car is connected by the chain 23 and an associated friction device with the rear end of the controlling rod 12 of a preceding car. As before described, the spring 14 normally holds the rod 12 retracted and the latch 10 in engagement with the brake member 8, thus preventing the latter from swinging downward into the path of the brake members 5, and the coupling member 19 is frictionally engaged by the member 20, whereby said coupling members are held from displacement. This frictional engagement between the members 19 and 20 is sufficient to hold them from longitudinal separation against the resistance of the spring 14 when the rod 12 is drawn forward, but not sufficient to prevent separation of said coupling members when a relatively greater pulling or draft strain upon the member 20 occurs as when the coupling 3 breaks, the said walls of the slotted or bifurcated portion of said member 20 being adapted under strain to spread and release said member from the member 19 when an excess pulling strain falls thereon. If, therefore, the coupling 3 between adjoining cars of a train should part, the forward

travel of the released car up the inclined track will cease and the car begin to travel backward by gravity. As a result the chain connection 23 will be drawn upon and will pull the rod 12 forward against the resistance of spring 14 to retract the latch 10 and free the brake member 8 for automatic action. As soon as this occurs the rod 12 has moved forward to its full extent and an increased pulling strain comes upon the chain connection 23, the coupling member 20 will be pulled apart from the coupling member 19, thus disconnecting rod 12 from the similar rod of the preceding car so as to avoid damage to the members of the brake gearing on the cars or prevent the car or cars which remain fastened to the draft cable from being derailed or otherwise injured. As soon as the brake member 8 is released by the latch, it will of course be understood that it will drop downward and engage one of the brake members 5 in the track, thus positively stopping the descent of the car before it can attain any considerable amount of speed or momentum.

From the foregoing description, taken in connection with the accompanying drawings, the construction and mode of operation of my automatic safety stop or brake mechanism for mining and other like cars will be readily understood, and it will be seen that a safety brake mechanism is provided whereby in the event of contingencies of the character mentioned in cars which may be freed from the draft mechanism will be automatically stopped and prevented from dashing down the inclined track-way, whereby accidents to life and property will be obviated.

I claim:

1. In a safety stop or brake for cars, the combination of a trackway, a brake along the trackway, a car adapted to travel upon said trackway, a brake device upon the car, a longitudinally movable rod carrying a latch to hold the brake device inoperative, a spring acting on the rod to hold the latch in normal engaging position, and a coupling device for connecting said rod to an element to which the car is coupled, said connection embodying coupling members adapted for disengagement following the actuation of the rod against the resistance of the spring to retract the latch.

2. In a combination with a car, a stop member on the car, a latch for holding said stop member inoperative, a controlling rod longitudinally movable and connected with the latch, a spring for holding the latch in normal engaging position, and a connecting element embodying coupling members adapted to separate after the rod has been moved against the resistance of the spring to a sufficient degree to retract the latch.

3. An automatic safety stop for cars in-

cluding a stop device on the car, a longitudinally movable rod on the car, a latch controlled by the rod to normally engage and hold the stop device retracted, a spring 5 acting on the rod to maintain the latch in normal engaging position, a coupling member on the rod, and a connection having a coacting coupling member, said coupling members being adapted for automatic separation after the rod has been moved against the resistance of the spring to a sufficient degree to retract the latch.

4. An automatic safety stop for cars including a pivoted gravity movable stop member on the car, a longitudinally movable rod on the car, a latch device controlled by the rod for holding the stop member retracted, a spring acting on the rod to normally maintain the latch in engaged position, a coupling member on the rod, and a connection having a co-operating coupling member adapted for engagement with the first-named coupling member and for separation therefrom after the rod has been 15

drawn upon to a sufficient degree against 25 the resistance of the spring to retract the latch.

5. A safety stop for cars including a brake member on the car, a longitudinally movable rod on the car, a latch controlled 30 thereby to engage and hold said brake member retracted, a spring acting on the rod to normally maintain the latch in engaging position, a coupling member on the rod, and a connection having a coacting coupling 35 member, said coupling members having an interfitting frictional engagement and being adapted for automatic separation after the rod has been drawn upon to a sufficient degree against the resistance of the spring 40 to retract the latch.

In testimony whereof I affix my signature in presence of two witnesses.

FRED J. MILLER.
